(57) **CLAIM**

The ornamental design for an illumination lense, is as shown and described.

DESCRIPTION

FIG. 1 is a perspective view of an illumination lense showing my design, where those indicated by broken lines are not claimed;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof, where those indicated by broken lines are not claimed; and,

FIG. 7 is a bottom plan view thereof, where those indicated by broken lines are not claimed.

The broken lines depict a portion of the illumination lense that forms no part of the claimed design.
